UNITED STATES PATENT OFFICE

RALPH WILLOUGHBY OSBORNE, OF TORONTO, ONTARIO, CANADA

COMMUNICATION SYSTEM

Application filed October 16, 1929, Serial No. 400,087, and in Canada August 6, 1928.

My invention relates to communication systems, and has special reference to protective means for systems that are subjected to transient disturbances due to their proximity to electric power transmission lines.

More particularly my invention refers to an electrical communication system which has one or more neutral points connected to ground for the drainage of extraneous current from the lines of the communication system to ground.

To those familiar with the art, it is well known that when the transmission line conductors of a communication system are parallel to an electric power transmission line, a potential is induced in the transmission line conductors of the communication system. Such potentials are particularly severe during transient disturbances in the power transmission system, necessitating the installation of protective devices in the communication system to protect its sensitive instruments and translating devices from damage. Besides the fuses and arresters which are used

in all wire communication systems, it is common practise to install a device known as a drainage coil comprising a high impedance winding wound on an iron core and having a neutral point which is grounded, the extremities of the winding being connected respectively to each transmission line conductor of the communication system. Drainage coils are so designed that they offer a low impedance to induced current in the line conductors, but a very high impedance to the currents used for the transmission of intelligence. A modification of the drainage coil comprises in addition to the winding and core enumerated above, a secondary winding thus

constituting a transformer, the extremities of the primary winding being connected respectively to each transmission line conductor, the neutral connected to ground, the secondary winding being insulated from the primary winding and its extremities connected to the conductors leading to the communication instrument or translating device.

During severe transient disturbances in the power transmission system heavy current is induced in the communication line conduc-

tors, which if permitted to flow through the winding of the drainage coil or transformer may burn out the winding. To protect the winding from burnout it is common practise to insert fuses between the winding and the line wires. These fuses may blow out frequently causing interruption to the communication of intelligence.

The object of my invention is to provide means for bypassing heavy extraneous current past the drainage coil or transformer winding directly to ground, and for automatically restoring the system to normal operating conditions when the extraneous current has subsided.

It is a further object of my invention to provide means for bypassing heavy extraneous current past the drainage coil or transformer winding directly to ground so as to permit using fuses of much larger capacity or in most cases dispensing with the use of fuses entirely.

In order to attain this object I provide a relay so arranged that it is actuated by extraneous current when such current exceeds a predetermined degree so as to close suitably arranged contacts for bypassing the current past the drainage coil or transformer winding to ground, and automatically releasing said contacts when the extraneous current subsides.

In order to understand my invention more fully reference may be had to the following description and accompanying drawing in which the single figure is a diagrammatic view of a communication system embodying a form of my invention.

Referring to the drawing it will be noted that I have shown a communication system using a transformer having a primary winding with the neutral point grounded, but it is apparent that my invention may be applied to a system employing a drainage coil. 1 and 2 represent the transmission line conductors of the communication system, 10 the relay with a pair of windings 3 and 4 connected respectively in series with the transmission line conductors 1 and 2 and wound around a common core 5 and continued by means of wires 25 and 26 to the extremities 100

of primary winding 13 of the transformer 11. 14 is the secondary winding of the transformer 11 connected to the translating device 23 by means of wires 21 and 22. The neutral 5 point 12 of the primary winding 13 of the transformer 11 is connected to ground 16 by means of wire 15. Contacts 8 and 9 are connected respectively by wires 19 and 20 to the extremities of primary winding 13 at points 10 17 and 18 on wires 25 and 26. A third contact 7 is carried by armature 6 which is hinged by pivot 27 and normally held against back stop 29 by spring 28. Contact 7 is grounded through armature 6 and wire 24 to ground 16. 15 It will be seen that when extraneous current flows from wires 1 and 2 through windings 3 and 4 of relay 10, through wires 25 and 26 and the two halves of the primary winding 13 of transformer 11, converging to 20 neutral point 12 and ground wire 15 to ground at 16, the currents in the two windings 3 and 4 of relay 10 will act cumulatively to magnetize core 5 and when the magnetic pull on armature 6 is sufficient to overcome the tension 25 of the spring 28, contact 7 will be drawn down and make contact simultaneously with both contacts 8 and 9, thus bypassing the current around the primary winding 13 of transformer 11 from points 17 and 18 through 30 wires 19 and 20, contacts 8 and 9, contact 7, armature 6 and wire 24 to ground at 16. It will also be seen that the current continues to flow through the relay windings after the contacts have closed which is necessary in 35 order to hold the contacts closed until the extraneous current subsides. When the current subsides the armature is released. It has been found by experiment that a relay can be designed with heavy wire windings enabling 40 them to carry heavy currents for considerable periods of time. In using the transformer with the ordinary fuse protection it frequently happens that one fuse blows leaving the other intact and allowing current to 45 pass through one half of the primary winding of the transformer with no opposing current in the other half of the winding, thus allowing a potential to build up which is transmitted to the secondary winding by induction, thence to the translating device. The 50 importance of maintaining a balance of the circuit is therefore apparent for the adequate protection of the communication instruments connected thereto and it will be seen that the 55 design and operation of my relay is such that this object is attained inasmuch that the two contacts are arranged to close and break simultaneously. This is accomplished by the simple expedient of arranging the contact 60 faces of contacts 8 and 9 so that they converge at an angle and providing the contact electrode 7 with two contact faces respectively in parallel with the contact faces of contacts 8 and 9. When my relay protection is employed 65 both sides of the circuit remain intact at all

times and when extraneous current becomes excessive the contacts close and bypass the transformer thus allowing a negligible current to flow through the transformer winding. It will be seen therefor that while the primary object of the invention is to protect the transformer by so doing better protection is afforded the translating instruments. The inductive properties of the relay windings also protect the transformer windings from high frequency disturbances that may be set up in the system. 70 75

While I have shown and described one embodiment of my invention, it will be understood that various modifications may be made without departing from the spirit and scope of the appended claims. 80

What I claim is:

1. A communication system comprising transmission line conductors, a translating device relatively connected thereto, a winding extending between the transmission line conductors and having a neutral point connected to ground thus providing a path for draining extraneous current in the said communication system to ground, and an electromagnetic means serially connected in the said path and adapted to operate automatically suitably arranged contacts for connecting to ground, both extremities of the said winding having a neutral point, when extraneous current in the communication system exceeds a predetermined degree and for disconnecting both extremities of the said winding from ground when the extraneous current subsides. 90 95 100

2. A communication system comprising transmission line conductors, a translating device relatively connected thereto, a winding extending between the transmission line conductors and having a neutral point connected to ground and a relay comprising a pair of windings connected respectively in series with each transmission line conductor and wound around a common core, a pair of contacts connected respectively to each extremity of the aforementioned winding having a neutral point, an armature carrying a third contact which is grounded and adapted to simultaneously make contact with both of the aforementioned pair of contacts when extraneous current in the said communication system exceeds a predetermined degree and to simultaneously break both contacts when extraneous current subsides. 105 110 115

3. A communication system comprising a translating device, transmission line conductors, conductors leading to said translating device, a transformer interposed in the circuit and having a primary winding extending between the transmission line conductors, said primary winding having a neutral point connected to ground, a secondary winding extending between the conductors leading to the said translating device and a relay comprising a pair of windings connect- 120 125 130

ed respectively in series with each transmission line conductor and wound around a common core, a pair of contacts connected respectively to each extremity of the aforementioned primary winding, an armature carrying a third contact which is grounded and adapted to simultaneously make contact with both contacts of the aforementioned pair of contacts when extraneous current in the said communication system exceeds a predetermined degree and to simultaneously break both contacts when extraneous current in said communication system subsides.

5 In testimony whereof I affix my signature
10 at the city of Toronto.
